APPARATUS FOR SCREENING PAPER PULP

Edwin Cowles, Cayuga, N. Y., assignor to The Cowles Company, Princeton, N. J., a corporation of New Jersey

Application April 11, 1940, Serial No. 329,037

3 Claims. (Cl. 92—32)

This invention relates to apparatus for screening paper pulp.

It is an object of the invention to provide improved means for vibrating the screen element, and improved means for supporting said screen element, whereby improved screening efficiency and improved accessibility for cleaning and repair are secured.

Other objects and advantages of the invention will appear hereinafter.

A preferred embodiment of the invention selected for purposes of illustration is shown in the accompanying drawings, in which,

Figure 1 is a top plan view.

Figure 2 is a section on the line 2—2 of Figure 3.

Figure 3 is a longitudinal section on the line 3—3 of Figure 1.

Figure 4 is a detail sectional view of one of the electro-magnets.

Figure 5 is a top plan view of one end of one of the electro-magnets.

Referring to the drawings, the apparatus comprises a container 1 of any suitable shape, herein shown in elongated rectangular form, in which is mounted a screen element 2 of iron or other suitable magnetic material.

According to the present invention, it is proposed to vibrate the screen element magnetically, and to apply the magnetic force directly to the screen, using the screen as an armature. Accordingly, a plurality of electro-magnets 3 are mounted in said container immediately below the screen element, but spaced therefrom. In the preferred embodiment illustrated, the said electro-magnets are elongated in form and extend lengthwise of the container from one end of the screen to the other. Four such magnet units are distributed at intervals across the container, so that substantially the entire area of the screen is within the effective field of the magnets.

The construction of the magnet units is illustrated in Figures 4 and 5. Each unit comprises a pair of U-shaped trough members 5 and 6, preferably of iron, laid parallel to each other, but spaced a short distance apart. A coil of conductor wire 7 is laid in said trough members, each winding of the coil extending lengthwise along one of said trough members to the end thereof, then around the end, then lengthwise of the other trough member in the opposite direction, and so on.

The trough members 5 and 6 are mounted in a larger trough 8, and the conductor wires are sealed in by a covering 9 of suitable protective

material such as asphalt or pitch which prevents penetration of the water in which the magnet units are immersed during operation of the apparatus. A copious amount of asphalt is used to fill all the interstices between the conductor wires and to fill any spaces remaining in the troughs after assembling the coils therein. Furthermore, the bottom of the trough 8 and the spaces at the ends of the trough 8, beyond the members 5 and 6, as well as the side spaces are filled. However, the space between the trough members 5 and 6 is not filled, but is left open to provide a groove for the reception of a strip 10 of relatively soft resilient material such as sponge rubber, for example.

The upper surfaces of the strips 10 engage and support the screen 2 and additional strips 11 of similar resilient material are mounted along the side and end walls of the container 1 to engage and support the outside edges or rim of the screen, along the entire periphery thereof. Thus, when the electro-magnets are energized, they tend to draw the screen down to slightly compress the resilient strips 10 and 11, and when the magnets are thereafter deenergized, the resilience of the strips 10 and 11 pushes the screen up again.

In conventional paper pulp screens it is necessary to use a fairly thick and heavy screen element in order to secure the required rigidity, and because of the thickness required the screen apertures are usually milled slots which are not only very expensive, but also seriously limit the capacity of the screen because of the relatively wide spacing required between slots. According to the present invention, however, because of the novel method of vibration and support of the screen element, it may be made of very light material. For example, a screen plate having a thickness of ".040'" has been found entirely adequate and ordinary drilled perforations having a diameter substantially equal to the thickness of the plate have been found satisfactory. Such perforations may be closely spaced and provide unusually high capacity.

The magnet units may be energized intermittently to vibrate the screen element by utilizing any of the well known electrical devices for supplying intermittent or pulsating current. For example, a relatively low frequency (60 cycles or less) alternating current may be used, or intermittent direct current may be used.

In the operation of the apparatus raw stock is flowed through inlet opening 15 to a head box 16 having a dam 17 over which the stock flows

onto the screen, being distributed by the dam over the entire width of the screen. Acceptable stock passes through the screen perforations, flowing back along the bottom of the container to the lower chamber 18 of the head box. Here a dam 19 maintains a liquid level sufficient to keep the screen immersed in the stock, and a dam 20 performs a similar function at the other end of the screen. Screened stock is withdrawn through outlet opening 21 and rejects or tailings are withdrawn through outlet opening 22. If desired a spray nozzle 23 may be located above the screen near the discharge end to shower water onto the screen to assist in the separation of good stock from tailings, and to wash the tailings toward the outlet opening 22.

Since the flow of stock through the screen element and the magnetic force both tend to hold the screen against the resilient strips 11, an adequate seal is provided at the edges of the screen to prevent flow of stock around the edges of the screen and between the screen and said strips. However, since no mechanical devices are required to hold the screen in place, it may be easily lifted out of the container to permit inspection, cleaning and repair.

It will be understood that the invention may be variously modified and embodied within the scope of the subjoined claims.

I claim as my invention:

1. In an apparatus for screening paper stock, in combination, a screen, resilient means in abutting contact with one face of said screen along the edges of said screen around the entire periphery thereof and sealing the edges of said screen to prevent flow of stock between said screen and

said resilient means, additional resilient means in abutting contact with the same face of the screen and distributed at spaced intervals over the surface thereof, and means to apply magnetic force intermittently to the screen over substantially the entire area thereof to draw said screen uniformly against all of said resilient means to compress the same substantially uniformly throughout the area of the screen.

- 5 2. In an apparatus for screening paper stock, in combination, a container, a screen in said container, resilient means in said container, said resilient means consisting of compressible material in abutting contact with the edges of said screen around the entire periphery thereof and sealing the edges of said screen to prevent flow of stock between said screen and said resilient means, and means for intermittently applying magnetic force directly to said screen to draw said screen against said resilient means to compress the same, said resilient means serving to move said screen in the opposite direction when said magnetic force is interrupted.
- 10 3. In an apparatus for screening paper stock, in combination, a container, a screen in said container, a plurality of electro-magnets in said container adapted to apply magnetic force directly to said screen, said electro-magnets being elongated and substantially co-extensive with said screen in one direction and distributed at intervals across said screen in the other direction, whereby substantially the entire area of said screen is within the effective field of said electro-magnets, and the entire area is moved through 15 substantially equal amplitudes.
- 20 4. In an apparatus for screening paper stock, in combination, a container, a screen in said container, a plurality of electro-magnets in said container adapted to apply magnetic force directly to said screen, said electro-magnets being elongated and substantially co-extensive with said screen in one direction and distributed at intervals across said screen in the other direction, whereby substantially the entire area of said screen is within the effective field of said electro-magnets, and the entire area is moved through 25 substantially equal amplitudes.

EDWIN COWLES.
